SELF-REGULATING AUTOMATIC TRAFFIC
CONTROL SYSTEM

Henry A. Haugh, Jr., New Haven, Conn., assignor,
by mesne assignments, to The Engineering and
Research Corporation, East Norwalk, Conn., a
corporation of Delaware

Application October 20, 1927, Serial No. 227,490

39 Claims. (Cl. 177—337)

This invention relates to automatic self-regulating traffic control systems and more particularly to a system for controlling vehicular traffic at highway intersections. A traffic control system embodying my invention is not limited in its use to the regulation of highway traffic but may be employed with equal facility at any intersecting traffic lanes wherein it is desired to automatically regulate the passage of traffic through the intersection by the presence of vehicles desiring to use the intersection. Such a system may be employed at railway crossings where it is desired to operate any convenient warning signal.

One fault of the ordinary "stop" and "go" installation employing signals for street traffic control, and regulated by a timing device which exhibits the signals in a periodic sequence without regard to traffic conditions, is that it frequently happens that the stop signal is turned against moving vehicles, in order to give the right of way to the traffic on the intersecting street when there are no waiting vehicles thereon. Another fault with such ordinary timed systems is that the right of way is retained on a street longer than required, causing vehicles on the other street to wait needlessly. These conditions needlessly delay traffic, and cause congestion at intersections.

The primary object of my invention is to provide a self-regulating traffic control system which shall be mechanically dependent upon actual volume and distribution of traffic. This object is accomplished by providing a mechanical system of traffic control which shall function in response to the particular condition of traffic flow, and operate the desired signal in response to the actual volume and distribution of traffic rather than upon any arbitrary time setting.

A further object of my invention is to provide a system of traffic control wherein an indicating signal is operated by the traffic through a timing mechanism, by the timing mechanism itself, or by both, in such a way:

1. That right of way is given successively to several traffic lanes in an order which may be predetermined but in such a way that the length of time which one lane retains the right of way is dependent upon either the approach of vehicles in said lane, upon the approach of vehicles in one or more other lanes, or upon both.

2. That a traffic lane which does not require the right of way cannot hold it to the disadvantage of one which does.

3. That a vehicle whose progress is prevented by a continuous stream of opposing traffic may

not be required to wait more than a fixed period of time, but that within this period is given right of way for as long as required for itself and following vehicles up to the aforementioned time limit.

4. That interfering lanes of traffic shall not be permitted to hold the right of way simultaneously.

5. That a vehicle which has passed the actuating means is protected against opposing traffic for a period of time sufficient to permit the said vehicle to pass the intersection of the traffic lanes.

6. That a vehicle which approaches an intersection on any lane of traffic is given immediate right of way on condition and only on condition that there be no opposing traffic in or immediately approaching the intersection.

7. That when a vehicle is not given immediate right of way or has right of way taken from it before it has had sufficient time to reach the intersection, the system will be left in such a condition that right of way will return to the delayed car at the earliest possible moment.

8. That continuous vehicular traffic in one lane is periodically interrupted to allow pedestrians to cross this lane even in the absence of vehicular traffic in the lane of the pedestrians.

9. That when the signal means and timing system is disconnected from the traffic actuated means right of way is given successively to the various traffic lanes according to a predetermined sequence and each for a predetermined time interval.

10. That by simple adjustments in the system, all fixed time intervals and responses to traffic in various lanes may be adjusted to meet various distributions and densities of traffic.

Other objects will be more manifest by reference to the following specification and drawings and specifically set forth in the claims.

In the drawings:

Fig. 1 is a diagrammatic view showing a highway intersection employing a signal system embodying my invention.

Fig. 2 is a diagrammatic view showing the circuits of an apparatus for operating the signal at intersecting traffic lanes.

Fig. 2a is an across the line arrangement of Fig. 2.

Fig. 3 is a detail view showing a section of a vehicle actuated contact device.

Fig. 4 is a wiring diagram for two contact devices in a traffic lane, and located at opposite sides of the intersection.

A self-regulating automatic traffic control system embodying my invention comprises three parts, a vehicle indicator placed in or at the side of the road, an electrical time limiting control system, and a signal device to indicate right of way to traffic. The function of the indicating device is such that a vehicle approaching the intersection of two or more traffic lanes actuates an electrical control circuit. The function of the electrical time limiting control system is to receive actuation produced by the vehicle and to pass this actuation on either instantly or after the passage of some timed period to the signal means which shall then warn the vehicle either to stop or shall give it the right of way. The signal means to inform the traffic in each street when to go and when to stop may be the standard red, yellow, and green lights now in general use, and these are mentioned in this description, but other means such as semaphore arms, horns, or bells or any other signal means may be used with equal facility. The vehicle actuated means may be of several types as hereinafter mentioned:

23 One means actuated by the approaching vehicle may be of a mechanical nature such as a mechanical switch located in the street or at the side of the street and electrical contact being made upon passage of the vehicle.

30 Another means for detecting and recording the presence of an approaching vehicle may be any beam of light projected across the highway and received upon a photo-electric or light sensitive electric cell so that an approaching vehicle causes an interruption or fluctuation in an electrical current passing through the light sensitive or photo-electric cell.

40 An electromagnetic device located in the street or at the side of the street may also be arranged in such a manner that an approaching vehicle shall actuate the device to interrupt an electric circuit.

45 The approaching vehicle may be caused to pass over a flexible tube placed across the highway, said tube containing a gas or a liquid. The vehicle crossing this tube could either interrupt a flow of gas or liquid within the tube thereby causing a mechanical switch to actuate the electrical circuit, or it might operate the mechanical switch merely through the accompanying change of pressure in a static gas or liquid in the flexible tube.

50 The time limit control circuit operates as follows: Assume that there are no vehicles approaching on the intersecting streets designated by A and B; a yellow signal light appears in both streets. A vehicle approaching from A-street now operates the A-street actuating means and contact relays immediately close the circuit, thus lighting the A-street-green and the B-street-red lights and simultaneously extinguishing the yellow lights in both streets. A-street now has the right of way. The device provides for relinquishing the A-street green light under any one of the following conditions:

1. When A-street traffic has all passed the intersection.
2. If A-street traffic is still moving at the end of a predetermined period (such as 30 seconds) the green light is yielded to permit pedestrians to cross A-street.
3. If A-street traffic is still moving at the end of the 30 second period and vehicles are waiting on B-street, the A-street green light is yielded in favor of B-street.

These limitations on the period during which A-street may hold the green light, are controlled by suitable time limit relays hereinafter described.

5 Provision to yield the A-street green light whenever the A-street traffic has passed the intersection (case 1 above) is made through the use of a time limit relay set to open the A-street-green and the B-street-red light circuit, after said relay has been continuously energized 10 for a predetermined period, as for example, 10 seconds. This relay is set back to its starting position at each time a vehicle operates the A-street actuating means. Hence if a small number of vehicles requiring the use of this intersection for only a short period is present on A-street this relay will function to yield the green light 10 seconds after the last vehicle has passed the A-street actuating means. The A-street green and the B-street red lights will now be 20 extinguished and a yellow light again shows in both streets. If, on the other hand A-street traffic is continuous the 10 second relay is constantly set back to its starting position, thus preventing it from interrupting the A-street-green and the 25 B-street-red light circuit. Under these conditions another time limit relay set for a predetermined period, say a thirty second period, functions. The action of this relay is described in the next paragraph.

30 To provide for case 2 mentioned above, in which continuous traffic on A-street must be interrupted to permit pedestrians to cross A-street, another time limit relay set to open the A-street green and the B-street red light circuit is connected so that it will be energized when A-street is given the green light. This relay is not set back to its starting point by vehicles passing the A-street actuating means. Hence it yields the right of way held by A-street 30 seconds after 40 said right of way was given, unless the ten second relay had previously functioned due to the cessation of A-street traffic.

35 The combined effect of these time limit relays causes A-street to hold the green light for the 45 full 30 second period only if traffic on A-street requires it, yielding said light before the 30 second period expires if all the A-street traffic has passed the intersection.

40 The control circuit is so arranged that when 50 A-street has yielded the green light under any of the above outlined conditions a yellow light is shown in both streets during a caution period. After the caution period waiting traffic determines which street is to get the right of way. 55 If traffic waits on both streets, that on B-street is given the green light. If there is waiting traffic on A-street only, the green light reverts to A-street. If there is no traffic waiting on either street the lights in both streets continue 60 to show yellow until a vehicle approaches. Right of way is then given immediately to the approaching vehicle. In the next paragraph this is expressed in terms of the functioning of the 65 actual apparatus.

65 If at the end of this yellow caution period, vehicles have operated the B-street actuating means since 10 seconds before said street last lost the right of way, the green light is given to B-street. If on the other hand no vehicles have 70 operated the B-street actuating means since 10 seconds before B-street last lost the green light, and vehicles have operated the A-street actuating means since 10 seconds before A-street last lost the green light, right of way returns to A-street 75

after the yellow caution period. If the actuating means in neither street has been operated since 10 seconds before said street last lost the green light, the yellow lights will remain lighted on both streets until a vehicle approaches. Right of way is then immediately given to an approaching vehicle on either street.

A vehicle might approach the intersection from A-street during the last few seconds of A-street's 10 second period. The light might shift after said vehicle had crossed the actuating means but before it had crossed the intersection thereby stranding said vehicle between the actuating means and the crossing. To permit a vehicle so 15 stranded to pass as soon as possible the circuit is so arranged that the operation of the A-street actuating means during the 10 seconds directly preceding the yielding of the A-street green light (when yielded by the 30 second relay only) causes 20 the green light to revert to A-street at the first opportunity thereby releasing the stranded vehicle. For this reason, the phrase in the preceding paragraph is worded "since 10 seconds before said street last lost the green light."

In this description time limit relays operating to limit the period during which A-street may hold the right of way were mentioned. Another set similar to that used to govern A-street would be provided to govern B-street when B-street 30 should have the right of way. Their operation is just as that described in the case of the A-street relays.

There is included in the relay system a pair of time limit relays set to operate after they have 35 been energized for a predetermined interval, for example, 2 seconds. The function of these relays is to govern the length of the cautionary period between the red and green light period.

While I have described above a self-regulating automatic traffic control system embodying my invention, and have shown that this invention is comprised of three main interconnected parts, I now describe in detail the construction of one complete and specific system embodying 45 my invention. Referring to Fig. 1 of the drawings there is shown a complete self-regulating automatic traffic control system applied to intersecting streets A and B. The vehicle actuated means are indicated by numbers 4, 5, 6, and 7. 50 The signal means in this particular embodiment is indicated at 9, and contains a red and a green electric lamp visible from either direction on A-street but not visible on B-street; a red and a green electric lamp visible from either direction on B-street, but not visible from A-street; and a yellow electric lamp visible from both streets. Energy is supplied to these electric lamps through the wires entering 9 as will be more completely described later.

The electrical time limiting control is indicated by 8. Fig. 1. Wires 10, 11, and 12 interconnect the A-street vehicle actuated means, while wires 10, 11, and 12 also connect these two means to the electrical time limiting control. Wires 13', 60 65 14 and 15, interconnect the vehicle actuated means on B-street, while wires 13, 14, and 15 also connect these two means to the electrical time limiting control. Figure 3 shows a vehicle actuated means constructed according to this particular embodiment, and numbers 90, 91, 92, and 93 indicate electrical contacts, which are so arranged that when a vehicle passes over the ramp arm 104, this ramp arm is pushed down, pivoting at 103, so that contacts 90 and 91 are separated and 70 75 contacts 92 and 93 are brought together. The

effect of a wheel passing over a ramp in A-street is to open the circuit between wires 11 and 12 by separating contacts 90 and 91, and then make a circuit between wires 10 and 11 by contact between 92 and 93. When the wheel has passed, 5 spring 103 causes arm 104 to rise separating contacts 92 and 93 thereby opening the circuit between wires 10 and 11 and re-establishes contact between 90 and 91 thereby re-establishing connection between wires 11 and 12 through contacts 10 94 and 95 on the other ramp on A-street. Fig. 4 indicates the way in which the two vehicle actuated means on any one street are interconnected in this embodiment of my invention. Contacts 96 and 97 parallel 92 and 93 and contacts 94 and 95 15 are in series with 90 and 91. Thus actuation of either ramp produces the same effect on the circuits. Fig. 2 or Fig. 2a, which disclose identical apparatus and circuits, show the construction and wire arrangement in detail of an electrical time limiting control which is constructed according to this particular embodiment, and indicates also the electrical connections of the signal means, as well as a vehicle actuated means 20 for each street. In Figs. 2 and 2a, 89 (Y) is a yellow light visible from both streets, 83 (BG) is a green light visible from B-street, 84 (AR) is a red light visible from A-street, 85 (AG) is a green light visible from A-street, 86 (BR) is a red light visible from B street. Ramp arms 104 and 104' 30 with their associated contacts represent vehicle actuated means on A-street and B-street respectively.

The control system includes the following relays: instantaneous operating contacts relays 26, 35 27, 34, 35 and 36; oil dash-pot relays 28 and 29 arranged to operate their armatures 30 seconds after their coils are energized; oil dash-pot relays 30 and 31 arranged to operate their armatures 10 seconds after their coils are energized; and oil 40 dash-pot relays 32 and 33 arranged to operate their armatures 2 seconds after their coils are energized. All of the oil dash pot relays release their armature immediately upon deenergization. The apparatus in the left half of Figs. 2 and 2a 45 controls the display of the A-street green signal 85 and the B-street red signal 86. That in the right half controls the display of the B-street green signal 83 and the A-street red signal 84. These two groups of apparatus are interconnected 50 in such a way as to prevent the simultaneous display of the green signals on both streets but to permit the green signal on either street to be displayed in response to traffic or by cyclic operation as will be more fully explained later. Furthermore these groups cooperate to display a yellow signal to both streets between changes in the green signal display as will be explained 55 later.

Power from a suitable source is supplied 60 through wires 121 and 116, the former wire being designated positive and the latter negative for convenience in referring to them.

CONNECTION I.—Referring to Fig. 2 or Fig. 2a 65 of the drawings, the wiring diagram shows the connections arranged for the operation of the system when the yellow light is visible from both streets in absence of traffic on either street.

CASE I.—Single vehicle approaching from A-street.—Assume a vehicle approaches on A street and actuates ramp 5, depressing bar 104, thereby opening contacts 90 and 91 and closing contacts 92 and 93. The bar 104 may be any portion of a contact device and is shown as a lever pivoted about point 103 and held in position by a spring 70 75

103' (see Fig. 3). Contacts 92 and 93 having been engaged, relay 26 is energized through the circuit including wires 121 and 110, switch 107, wire 11, contacts 92 and 93, wire 10, switch 107, wire 139, the coil of relay 26 and wires 111' and 116. In Fig. 2 wire 111' connects with wire 116 through wire 111. Armatures 45 and 49 of relay 26 are now moved into their operated position. The engagement of armature 45 with contact 46 completes a holding circuit supplying positive power to the coil of relay 26 so that this relay will remain energized after the vehicle has passed ramp 5 and permitted contacts 92 and 93 to separate again. This holding circuit includes wire 140, armature 45, contact 46, wires 112 and 151, contact 61, armature 59 and wires 126 and 121.

The engagement of armature 49 with contact 50 energizes relay 34 through a circuit including wires 116 and 111, armature 49 and contact 50, wires 117 and 118, armature 98 and contact 99 of relay 36, wire 177, switch 105, wire 119, the coil of relay 34, wire 120, switch 105, wire 149, contact 67, armature 65, and wires 161 and 121. The armatures 71 and 77 of relay 34 now assume their operated positions.

The separation of armature 71 from contact 72 extinguishes the yellow signal 89 which had been energized through wires 121 and 142, armature 71, contact 72, wire 143, signal 89, wire 146, contact 75, armature 74 of relay 35 and wires 148 and 116.

The engagement of armature 71 with contact 13 energizes the A street green signal 85 and the B street red signal 86 through wires 121 and 142, armature 71, contact 78, wire 144, signals 85 and 86 in parallel, wires 87 and 116.

The engagement of armature 71 with contact 78 completes a second holding circuit supplying positive power to the coil of relay 26. This circuit includes wire 140, armature 45 and contact 46 of relay 26, wires 112 and 151, contact 78, armature 77 and wires 122 and 121. The purpose of this second holding circuit is to cause relay 26 to remain energized while relay 34 remains energized even though the first traced holding circuit for relay 26 may be opened by the separation of armature 59 from contact 61 of relay 30 which will occur under circumstances to be explained later in these specifications.

50 The separation of armature 77 from contact 79 of relay 34 deenergizes relay 33 which had been energized through a circuit including wires 121 and 122, armature 77, contact 79, wire 127, the coil of relay 33, wire 158, armature 57 and contact 58 of relay 29, wire 159, contact 63 and armature 62 of relay 31 and wires 123 and 116.

55 Armature 68 of relay 33 now assumes its unoperated position. The separation of armature 68 from contact 70 assures that relay 35 will remain deenergized, with the B street green signal consequently also deenergized, until relay 33 again operates which can occur only after the A street green signal has been extinguished and a period of yellow caution signal display has followed.

The engagement of armature 68 with contact 69 energizes timing relays 28 and 30. The circuit through which relay 28 is energized includes wire 121, switch point 24 and switch 18, wire 132, the coil of relay 28, wires 175 and 124, contact 69, armature 68 and wires 160 and 116. The circuit through which relay 30 is energized includes wires 116 and 160, armature 68, contact 69, wires 124 and 176, the coil of relay 30, wire 138, switch 107, wire 12, contacts 90 and 91 associated with ramp

arm 5 in A street, wire 11, switch 107 and wires 110 and 121.

5 Relays 28 and 30 thereupon begin to time their periods. If no other vehicle approaches from A street and contacts 90 and 91 consequently remain in continuous engagement, relay 30 will be continuously energized. At the end of its time period, assumed here to be 10 seconds, relay 30 will operate to terminate the A street green signal display as follows. The separation of armature 10 59 from contact 60 opens the circuit energizing the coil of relay 32. This circuit included wires 121, and 126, armature 59, contact 60, wire 113, contact 56, armature 55, wire 114, the coil of relay 32, wire 115, contact 82, armature 80 and wires 38 15 and 116.

10 Armature 65 of relay 32 now separates from contact 67 and makes contact with 66 thereby de-energizing relay 34 and through wire 125 energizing relays 29 and 31. The circuit for relay 29 20 includes wire 116, switch point 25 and switch 19, wire 155, the coil of relay 29, wires 174 and 125, contact 66 and armature 65 and wires 161 and 121. Positive power is supplied to the coil of relay 31 through the same circuit which feeds the 25 left coil terminal of relay 29 since wire 125 connects with both wire 173 and wire 174. Relay 31 gets negative power through wire 109, switch 108, wire 13, contacts 133 and 134 associated with ramp arm 104', wire 14, switch 108 and wires 172 30 and 116. The de-energization of relay 34 causes armature 71 to break from contact 73 and make contact with 72, thereby extinguishing green light 85 and red light 86 and lighting the yellow light 89. When relay 34 is de-energized, armature 77 35 breaks from contact 78 and makes contact with 79. Breaking contact 78 opens the holding circuit and releases the armature of relay 26, thus dropping it back to its normal unoperated position. The other holding circuit for relay 26, 40 previously mentioned, is open due to the separation of armature 59 from contact 61 of relay 30. Armature 77 making contact with 79 energizes relay 33 through a previously traced circuit. Two seconds after relay 33 is energized, armature 45 68 breaks from contact 69 thereby de-energizing relays 28 and 30 and makes contact 70. The de-energizing of relay 28 has no effect on the circuit inasmuch as it had not been energized continuously for 30 seconds. The release of relay 30 50 causes armature 59 to make contact with 60 and 61 thereby energizing relay 32 from wire 126 through its previously traced circuit, which, after 2 seconds, causes armature 65 to break from contact 66 thereby de-energizing relays 29 and 31 55 and make contact with 67. The de-energizing of relays 29 and 31 has no effect on the circuit, inasmuch as neither had been energized long enough to operate. A yellow light is now shown in both streets and the entire system has returned to its 60 original condition.

65 **CASE II.—Continuous traffic on A-street with no traffic on B-street.**—If in the preceding operation no cars had approached the intersection from B street, but vehicles had approached on A street each actuating an A street ramp either 5 or 7 within 10 seconds of the previous actuation of either ramp thereby breaking the coil circuit of 10 second relay 30 at contacts 90 and 91 and so preventing the operation of relay 30, 70 then armature 59 would have maintained a continuous contact with 60 and 61, thus preventing 10 second relay 30 from causing the circuit to operate as in Case I so as to extinguish green light 85 showing in A street and red light 86 75

showing in B street, and in addition providing that current flow through the coil of relay 26, through armature 45 and contact 46 even after armature 71 shall have broken contact from 78. The purpose of this is brought out later. The 30 second time-limit relay 28 which was energized through its previously traced circuit at the same time that 10 second relay 30 was energized, breaks the circuit between armature 55 and contact 56 30 seconds after it is energized, thereby releasing the 2-second time limit relay 32. Armature 65 breaks from contact 67 thereby interrupting the current operating relay 34. Armature 71 breaks contact from 78 and makes contact with 72 thereby extinguishing green light 85 showing in A street and red light 86 showing in B street, and lighting the yellow light 89. Armature 71 breaks from contact 78 but in this particular case does not interrupt the current operating relay 26 because of the fact that said current is supplied through contacts 59 and 61 on relay 30 which are connected in parallel with contacts 71 and 78. The fact that relay 26 therefore remains energized causes lights 85 and 86 to show after yellow light 89 has been lighted for 4 seconds as is explained in detail in the subsequent discussion, thus returning the right of way to A street after giving pedestrians a 4 second period in which to cross A street. The actual operation of the circuit to produce this effect is as follows. Armature 71 connects with contact 79, thereby energizing the 2 second time limit relay 33 as before described. Two seconds after relay 33 is energized armature 68 breaks from contact 69 thereby opening the circuit to relays 28 and 30 through wire 124, whereupon armature 55 makes contact with 56, thereby energizing 2 second relay 32. Two seconds after relay 32 is energized, armature 65 makes contact with 67, thereby energizing relay 34 whereupon armature 71 breaks from contact 72 thus extinguishing the yellow light and makes contact with 73 thus lighting the A street green light 85 and the B street red light 86. This cycle of operations repeats as long as vehicles operate either ramp in A street within intervals of 10 seconds and none operate a ramp in B street. In the event that vehicles fail to operate either A street ramp within an interval of 10 seconds, the subsequent operation is as described in Case I.

CASE III.—One vehicle on A street followed within 10 seconds by one vehicle on B street.—Under this condition, the circuit operates as in Case I with the following changes. When relay 34 is de-energized through the breaking of armature 65 from contact 67, armature 71 makes contact with 79. A vehicle operates either ramp 4 or 6 in B street which causes current to flow through the coil of relay 27. The contacts of ramps 4 and 6 control relay 27 just as contacts in ramps 5 and 7 control relay 26, and they control relay 31 just as contacts in ramps 5 and 7 control relay 30. The actuation of ramp 6 causes contacts 153 and 154 to engage thus energizing relay 27 through a circuit including wires 116 and 172, switch 108, wire 14, contacts 153 and 154, wire 15, switch 108, wire 156, the coil of relay 27 and wires 130' and 121. In Fig. 2 wire 130' connects with wire 121 through wire 130. Relay 27 is now held in the operated position by current flowing through wire 157, armature 47 and contact 48, wires 131 and 152, contact 64, armature 62 and wires 123 and 116. Armature 71 making contact with 79 energizes relay 33

through contacts 67, 68, 69, and 62. Two seconds after relay 33 is energized, armature 68 makes contact with 70 thereby operating relay 35 through wires 116 and 160, armature 68, contact 70, wire 150, switch 106, wire 128, contact 101, armature 100, wires 129 and 137, contact 53, armature 52, and wires 130 and 121. The separation of armature 68 from contact 69 deenergizes relays 28 and 30. Relay 30 which has been operated now assumes its unoperated condition. The operation of relay 35 causes armature 74 to break contact from 75 thus extinguishing the yellow light and to make contact with 76 thereby lighting the green light 83 on 15 B street and red light 84 on A street. The circuit for the B street green and the A street red light includes wire 88, lamps 83 and 84 in parallel, wire 147, contact 76, armature 74 and wires 148 and 116. Thus the effect has been that the vehicle in A street has retained the right of way for 10 seconds and at the end of this 10 second period, the signal has gone through the cautionary yellow period to an indication of right of way on B street.

When relay 35 was energized armature 80 broke the circuit with contact 82 and made contact with 81. Breaking of the circuit between 80 and 82 causes relay 32 to remain de-energized after armature 59 has made contact with 60 and 61. When relay 32 was originally deenergized by the separation of armature 59 from contact 60, as explained in Case I, armature 65 made contact with 66 thereby energizing time limit relays 29 and 31 the circuits for which have been traced previously. Ten seconds after relay 31 was energized, due to the fact that neither ramp in B street had been operated by a second vehicle, which would have de-energized relay 31, armature 62 breaks contact with 63 and 64 thereby de-energizing relay 33 thus permitting armature 68 to break contact from 70 and make contact with 69. The breaking of the circuit between 68 and 70 de-energized relay 35, thus breaking contact between 74 and 76 thereby extinguishing green light 83 and red light 84 and making contact between 74 and 75 thus lighting the yellow light 89. The separation of armature 80 from contact 81 deenergizes relay 27 which had been energized through a circuit including wires 116 and 88, armature 80, contact 81, wires 152 and 131, contact 48, armature 47, wire 157, the coil of relay 27 and wires 130' and 121. In Fig. 2 wire 130' connects with wire 121 through wire 130. Armature 80 in making contact with 82 energizes the 2 second relay 32 through contacts 55, 56, 60 and 59 on relays 28 and 30. Two seconds after relay 32 is energized armature 65 makes contact 67 and breaks from contact 66 thereby de-energizing time limit relays 28 and 31. In as much as relay 28 had not been energized for a sufficient length of time to operate its armature, it has not acted to control the circuit. The de-energizing of relay 31 permits armature 62 to make contact with 63 and 64 thereby energizing relay 33, through armature 77 and contact 79. Two seconds after relay 33 is energized, armature 68 breaks from 68 thereby de-energizing relays 28 and 30 and makes contact with 70 so that relay 35 operates immediately when relay 27 is energized. The circuit has now completed its cycle and has returned to the condition at the beginning of Case I, and as shown in Fig. 2 and Fig. 2a.

CASE IV.—*Continuous traffic on A street with one vehicle waiting on B street.*—Under these conditions, the circuit operates as outlined in Case II until a vehicle operates one of the ramps in B street. The opening of the circuit between contacts 55 and 56 which occurs 30 seconds after relay 28 is energized, de-energizes relay 32 causing armature 65 to break from contact 67 and make contact with 66. Connecting armature 65 with contact 66 energizes relays 29 and 31. Breaking the circuit between armature 65 and contact 67 de-energizes relay 34 whereupon armatures 71 and 77 fall back extinguishing the A street green light 85 and the B street red light 86 through breaking the circuit between armature 71 and contact 73. Armature 71 making contact with 72 lights the yellow light 89. Armature 77 breaking from contact 78 does not de-energize relay 26 because current for relay 26 is supplied through wire 126, armature 59 and contact 61, wires 151 and 112, armature 45 and contact 46 and wire 140. In the meantime vehicle has operated one of the ramps on B street energizing relay 27. Current to keep relay 27 energized after said vehicle has crossed the ramp flows through armature 47, contact 48, contact 64, and armature 62. Armature 52 now makes contact with contact 53. Armature 71 which made contact with contact 79 when relay 34 was de-energized thereupon energized relay 33 through contacts 57, 58, 63, and 62. Two seconds after relay 33 is energized armature 62 breaks from contact 69 thereby de-energizing relays 28 and 30. Armature 68, through making contact with contact 70, now energizes relay 35 through switch 106 and contacts 101, 100, 53, and 52. Armature 74 now breaks from contact 75, thus extinguishing the yellow light, and makes contact with 76, thereby lighting the B street green light 83 and the A street red light 84. Armature 80 breaks from contact 82 and makes contact with 81 thereby causing relay 32 to remain de-energized despite the closing of contact 55 with contact 56. Armature 65 therefore remains in contact with 66 keeping relay 29 energized and also relay 31 energized, inasmuch as this case assumes that a second car does not pass over a B street ramp. Hence 10 seconds after relay 31 was energized armature 62 breaks from contact 63 and contact 64 thereby de-energizing relay 33. Armature 68, of relay 33, now breaks from contact 70 and makes contact with 69 thereby energizing relays 28 and 30. Relay 35 is now de-energized through the break between armature 68 and contact 70. Armature 74 now breaks from contact 76 thereby extinguishing the B street green light 83 and the A street red light 84. The yellow light 89 is now lighted through armature 74 and contact 75. Armature 80 at the same time breaks from contact 81 thereby de-energizing relay 27 inasmuch as armature 62 is not now in contact with 64. Armature 80 makes contact with contact 82 thereby energizing relay 32 through contacts 55, 56, 59, and 60. Two seconds after relay 32 is energized, armature 65 breaks from contact 66, thereby de-energizing relay 29 and relay 31, and makes contact with 67, thereby energizing relay 34 through switch 105, contacts 99, 98, wires 118 and 117, contacts 50 and 49. Armature 71 now breaks from contact 72 extinguishing the yellow light and makes contact with 73 again lighting the A street green light 85 and the B street red light 86. Armature 77 also breaks from contact 79 thereby insuring that relay 33 remain de-ener-

gized even though armature 57 be in contact with 58 and armature 62 be in contact with 63. Armature 71 now makes contact with 78 thus paralleling armature 59 and contact 61. The system has now returned to the condition in which it was when the single vehicle actuated the ramp in B street. In this description we have shown how continuous traffic in A street would be interrupted for a sufficient period to allow a single vehicle from B street to use the intersection, and how right of way would return immediately thereafter to A street in which the continuous stream of traffic had been interrupted.

CASE V.—*Continuous traffic in both streets.*—Under these conditions the circuit operates as it did in Case IV to transfer the right of way from A street to B street. But, continuous traffic in B street opens the contacts in the B street ramps through which the current energizing relay 31 passes. Armature 62 therefore continues to make contact with 63 and 64. Relay 33 therefore remains energized until armature 57 breaks from contact 58 which will take place 30 seconds after relay 29 is energized. The energizing of relay 29 is caused in accordance with the description given in Case I. Armature 57 now breaking contact with 58 de-energizes relay 33. Armature 68 breaks contact from 70 and makes contact with 69 thereby de-energizing relay 35 and energizing time limit relays 28 and 30. Armature 74 now breaks contact with 76, thereby extinguishing B street green light 83 and A street red light 84, and makes contact with 75 thereby lighting the yellow light. Armature 80 now breaks from contact 81 which action has no effect on the circuit inasmuch as this connection is also made by armature 62 and contact 64. Armature 80 makes contact with 82 thereby energizing relay 32. Two seconds after relay 32 is energized, armature 65 breaks from contact 66 thereby causing the de-energizing of relays 28 and 31, thereby causing armature 57 to make contact with 58. Armature 65 makes contact with 67 thereby energizing relay 34 through switch 105, contacts 99, 98, 50 and 49. Armature 71 now breaks from contact 72 extinguishing the yellow light and makes contact with 73 lighting the A street green light 85 and the B street red light 86. Armature 77 breaks from contact 79 thereby causing relay 33 to remain de-energized even though armature 57 makes contact with 58 and armature 62 makes contact with 63. Armature 71 now makes contact with 78 and the circuit has returned to the condition in which it was at the beginning of this description.

CONNECTION II.—The operations described above under the headings Cases I, II, III, IV, and V, occur when the various switches are in the positions shown in Fig. 2 and Fig. 2a of the drawings. It may be seen from an inspection of Fig. 2 or Fig. 2a that if switch 16 is closed, relay 26 is continuously energized through wires 121 and 110, switch 16, wire 139, the coil of relay 26, and wires 111' and 116. In Fig. 2 wire 111' connects with wire 116 through wire 111 thereby causing the right of way to return to A street after every yellow period preceded by a B street green period or by an A street green period if neither B street ramp has been operated since 10 seconds before B street last lost the right of way, thereby insuring that relay 27 is de-energized.

CONNECTION III.—It can readily be seen by inspection of Fig. 2 or Fig. 2a of the drawings that 75

if the switches are as shown except that switch 17 is closed, the operation is as described in the last paragraph, except that the conditions described for A street and B street are interchanged.

CONNECTION IV.—It can be seen that with both switches 16 and 17 closed, the right of way is granted alternately to each street and is held by each street for any period between 10 and 30 seconds. If no vehicles actuate the ramp in a given street during a period of 10 seconds the 10 second relay functions to yield the right of way. If, on the other hand, when said street is given the right of way, vehicles operate either 15 ramp in said street at intervals of less than 10 seconds, the 10 second relay is repeatedly set back to its de-energized condition in which case the 30 second relay functions to yield the right of way 30 seconds after it is granted.

CONNECTION V.—It can be seen by an inspection of Fig. 2 or Fig. 2a of the drawings that if all the switches are as shown except that switch 21 makes contact with 38, then the opening of contacts 59 and 60 does not de-energize 25 relay 32 unless relay 21 has been energized by a car operating either ramp on B street. As long as relay 21 is deenergized relay 32 is connected to positive power through wire 114, armature 55, contact 56, wire 113, switch 21, switch point 38, 30 wire 135, contact 54, armature 52, and wires 130 and 121. Hence the 10 second relay 30 does not operate to cause the circuit to take the right of way from A street unless a vehicle has operated one of the ramps on B street, since 10 seconds before B street last lost right of way. With this connection the yellow signal is displayed to both streets in the absence of traffic. Any B street actuation will cause right of way to be granted thereto for 10 seconds which period 40 is extendable up to thirty second by subsequent B street actuations occurring at intervals of less than 10 seconds. An A street actuation will cause right of way to be granted thereto for a period of thirty seconds in the absence of any B street actuation. At any time after the first 10 seconds of this A street right of way period a B street actuation will immediately cause the yellow signal to be displayed after which right of way will be granted to B street except that A 45 street actuations occurring at intervals of less than ten seconds can maintain the A street right of way up to a 30 second limit.

CONNECTION VI.—It can also be seen that with all switches as shown in Fig. 2 or Fig. 2a of the drawings, except that switch 20 makes contact with 37, the operation is as described above except that conditions on A street and B street are interchanged.

CONNECTION VII.—It can also be seen from an inspection of Fig. 2 or Fig. 2a of the drawings that with all switches as shown except that switch 18 is moved from contact with 24 to 22, relay 28 is energized only when relay 27 shall have been operated by a vehicle actuating one 50 of the ramps in B street. Therefore in the event of continuous traffic on A street in which the A street ramps are operated at intervals of less than 10 seconds, A street continuously holds the right of way unless a vehicle on B street has actuated 55 a ramp on that street since 10 seconds before B street last lost right of way, energizing relay 27 which energizes relay 28 through contacts 52 and 53. Thirty seconds after relay 28 is energized, it functions to take the right of way from 60 A street. The cessation of A street traffic will

cause the right of way to be transferable to B street by action of relay 30 before the 30 second period or relay 28 has expired.

CONNECTION VIII.—If the switches are as shown in Fig. 2 or Fig. 2a of the drawings, except that switch 19 is moved from contact with 25 to 23 the conditions are as described in the above paragraph except that the conditions on A street and B street are interchanged.

CONNECTION IX.—If the switches are as shown 10 in Fig. 2 or Fig. 2a of the drawings except that switch 18 makes contact with 22 and switch 21 makes contact with 38, right of way remains with A street, once it is granted, continuously whether or not an A street ramp is actuated 15 until a vehicle on B street has operated a ramp on B street since 10 seconds before B street last lost right of way.

The operation of relay 27 de-energizes relay 32 by opening contacts 52 and 54 providing the 20 10 second relay 30 has already operated to open contacts 59 and 60. In the event that a vehicle has operated the A street ramp within an interval of 10 seconds, armature 59 will be in contact with 60 thereby supplying current to relay 25 32, despite the opening of contacts 52 and 54. Upon the expiration of the 10 second period following the operation of either A street ramp, armature 59 breaks from contact 60 thereby de-energizing relay 32, relay 27 being energized 30 which immediately causes the right of way to be taken from A street. If, on the other hand, vehicles on A street operate the A street ramps at intervals of less than 10 seconds, thus causing armature 59 to remain in contact with 60, 35 relay 28 operates to open contacts 55 and 56 thereby de-energizing relay 32 thirty seconds after the energizing of relay 27 by a B street ramp actuated by a vehicle.

CONNECTION X.—It may be seen from Fig. 2 or Fig. 2a of the drawings that if the switches are as shown, except that 19 makes contact with 23, and 20 makes contact with 37, the operation is as described in the above paragraph except that conditions in A street and B street are interchanged.

CONNECTION XI.—It can be seen from Fig. 2 or Fig. 2a of the drawings that if the switches are as shown except that switch 16 is closed and switch 18 makes contact with 22, and switch 21 makes contact with 38, right of way reverts to A street, after each yellow period succeeding a period during which B street held the right of way. A street then holds said right of way until the end of the minimum period of 10 seconds of relay 30 after which right of way is instantly yielded in response to B street actuations if no A street actuation has occurred during the preceding 10 seconds, or right of way is yielded by the operation of relay 28, thirty seconds after 60 relay 28 is energized, if continuous traffic on A street prevents the 10 second relay from yielding the said right of way. Relay 28 is energized through contacts 52 and 53 which contact is made when relay 27 is energized.

CONNECTION XII.—It may be seen from inspection of Fig. 2 or Fig. 2a of the drawings that if all switches are as shown except that switch 17 is closed, switch 19 makes contact with 23, and switch 20 makes contact with 37, the conditions 70 are as outlined in the above paragraph except that the conditions indicated for A street and B street are interchanged.

CONNECTION XIII.—It may be seen from inspection of Fig. 2 or Fig. 2a of the drawings that 75

with the switches as shown except that switch 16 is closed and switch 21 makes contact with 38 right of way is given to A street after each yellow period before which B street had right of way or succeeding a period during which A street held the right of way, unless a vehicle has actuated a B street ramp since 10 seconds before B street last lost right of way. It can be seen that under these conditions if no vehicles operate either of the B street ramps during an extended period, right of way is held by A street continuously except that every 30 seconds a yellow period of 4 seconds is introduced during which time the A street green and the B street red lights are extinguished. Immediately following this period, right of way returns to A street. This yellow period is inserted to permit pedestrians to cross A street. With the switches as described in this case, if a vehicle operates a B street ramp, thereby energizing relay 21, right of way is given to B street immediately after an intervening yellow period providing no vehicle has operated either of the A street ramps during the preceding 10 seconds and provided that the A street minimum period of 10 seconds has expired. If, on the other hand, a vehicle has operated either of the A street ramps during the 10 second period immediately preceding the operation of the B street ramps, relay 32 is energized through contacts 59 and 60 despite the fact that the circuit is open between contact 52 and 54. Armature 59 is in contact with 60 because under the above conditions relay 30 has not been energized continuously for 10 seconds. In the event that vehicles operate the A street ramps at intervals of less than 10 seconds relay 28 functions 30 seconds after right of way is given to A street to yield said right of way by de-energizing relay 32 through breaking the circuit between 55 and 56. In this part of the discussion, I have not traced the action beyond relay 32, since the operation subsequent to the de-energizing of relay 32 is always the same up to the point at which relay 34 turns off the A street green and the B street red and turns on the yellow light, these being accomplished respectively by breaking of armature 71 from contact 73 and making of contact between 71 and 72. This action takes place upon the de-energizing of relay 34 which is accomplished through armature 65 breaking from contact 67 when relay 32 is de-energized.

CONNECTION XIV.—It may be seen by reference to Fig. 2 or Fig. 2a of the drawings that if the switches are in the position shown except that switch 17 is closed and switch 20 makes contact with 37, the operation is as described in the preceding paragraph, except that the conditions on A street and B street are interchanged.

CONNECTION XV.—The circuit is so arranged that if it is desired to disconnect the traffic actuated means for any reason, this can be accomplished by throwing switch 107 so that it makes contact with 41, 42, and 42', breaking contact from 10, 11, and 12, and throwing switch 108 so that it makes contact with 43, 43', and 44 breaking contact with 13, 14, and 15. Under these conditions relays 26 and 27 are continuously energized through 41 and 42, 43 and 44, and the coils of relays 30 and 31 are disconnected from contacts 12 and 13 respectively, thereby causing said relays to be continuously de-energized. An inspection of Fig. 2 of the drawings shows that independent of the position of switches of 16, 17, 18, 19, 20, and 21, the system operates to give right of way alternately to each street for 30

seconds, introducing a 2 second yellow period at each transfer. In this case, the action is as follows: Assume that the relays are as shown in Fig. 2 and Fig. 2a and that switch 107 is thrown to this new position before 108 is thrown to its new position. Hence relay 26 being the first to be energized, gives right of way to A street in the following manner: Armature 49 breaks from 51 and makes contact with 50 thus connecting to the power supply one terminal of the 10 coil of relay 34 through wire 118, armature 98, contact 99, and switch 105. The other coil terminal of relay 34 is connected to the other side of the power supply through armature 65 and contact 67 of relay 32. Relay 34 now being 15 energized, armature 71 now breaks from contact 72 thereby extinguishing the yellow light and makes contact with 73 thereby lighting the A street green light 85 and the B street red light 86. Armature 71 breaks from contact 79, thereby 20 causing relay 33 to be de-energized. Armature 68 breaks from contact 70, thereby preventing any current from energizing relay 35, and makes contact with 69 thereby energizing the coil of relay 28. Thirty seconds after the coil of relay 25 28 is energized, armature 55 breaks from contact 56, thereby de-energizing relay 32, whereupon armature 65 breaks from contact 67 and makes contact with 66 thereby de-energizing relay 34 and energizing relay 29. When relay 34 is de-energized, armature 71 breaks from contact 73, thereby extinguishing the A street green light and the B street red light, and makes contact with 72, thereby lighting the yellow light. Armature 71 makes contact with 79, thereby energizing 35 relay 33. Two seconds after relay 33 is energized, armature 68 breaks from contact 69, thereby de-energizing relay 28 and causing armature 55 to make contact with 56. Armature 68 makes contact with 70 thereby energizing relay 35 40 through contacts 53 and 52. Thereupon, armature 74 breaks from contact 75 extinguishing the yellow light and makes contact with 76, thereby lighting the B street green and the A street red lights. Armature 80 breaks from contact 82 causing relay 32 to remain de-energized despite the closing of contacts 55 and 56. Thirty seconds after relay 29 is energized, armature 57 breaks from contact 58, thereby de-energizing relay 33, whereupon armature 68 breaks from 50 contact 70, thereby de-energizing relay 35 and makes contact with 69, thereby energizing relay 28. Relay 35 now being de-energized, armature 74 breaks from contact 76, extinguishing the B street green and the A street red light and makes contact with 75, thereby lighting the yellow light. Armature 80 makes contact with 82, thereby energizing relay 32. Two seconds after relay 32 is energized, armature 65 breaks from contact 66, de-energizing relay 29 and makes contact with 67, 60 energizing relay 34. Relay 34 now turns on the A street green and the B street red lights and extinguishes the yellow light. This cycle now repeats.

CONNECTION XVI.—If it is desired to disconnect 65 the traffic actuated means in A street and leave connected the traffic actuated means in B street, this may be accomplished by leaving the switches as shown in Fig. 2 and Fig. 2a of the drawings, except that switch 107 is operated to the position 70 making contact with 41, 42, and 42'. Under this condition, right of way will remain on A street for a period of 30 seconds regardless of actuation of an A street ramp, and remains on B street for a period dependent upon the actuation of the B 75

street ramps, varying from 10 to 30 seconds. Right of way is given to B street following a yellow period only if a B street ramp has been actuated since 10 seconds before B street last lost right of way. In the absence of B street actuations a yellow signal period alternates with an A street right of way period, with the yellow period inserted for 4 seconds every 30 seconds.

CONNECTION XVII.—Likewise switch 108 may 10 be operated to its other position instead of switch 107, thus producing the effect described in Connection XVI except that the condition on A street and B street are interchanged.

The circuit is so arranged that manual control 15 may be used. This is accomplished as follows through the use of switches 105 and 106. To show a yellow light in both streets, switches 105 and 106 are operated to such a position that the blades 20 make no contact. Thereupon, relays 34 and 35 are de-energized and the yellow light is lighted through contacts 71, 72, 74, and 75. To light the A street green and the B street red lights, the 25 blades of switch 105 are thrown to the left contacts thereby energizing relay 34 through wires 166 and 167, extinguishing the yellow light by interrupting its circuit between 71 and 72, and lighting the A street green and the B street red through the contacts made between armature 71 and contact 73. To light the B street green and 30 the A street red lights, the blades of switch 106 are thrown to the right contacts, thereby energizing relay 35 through wires 164 and 165. Armature 74 breaking from contact 75 opens the yellow light circuit, and armature 74 making contact 35 with 76 lights the B street green and the A street red lights.

The circuit is so arranged that the yellow light can be turned on and all other signal lights extinguished either by closing switch 102 shown in Fig. 2, and Fig. 2a or by applying power to the two wires marked "To fire headquarters." This feature is introduced to provide for emergency control either at the control panel at the intersection, or from a distant point. Either of the 45 last two described operations energize relay 36, thereby breaking contact between 100 and 101 and 98 and 99, thus deenergizing relays 34 and 35, causing armature 71 to make contact with 72 and armature 74 to make contact with 75, thereby 50 by lighting the yellow light and preventing any other signals from being lighted except by manual operation as previously described. Closing switch 102 energizes relay 36 through wire 121, switch 102, wire 171 and 169, the coil of relay 36, 55 wire 168 and 170, switch 102 and wire 116.

The circuit is so arranged that if the right of way is yielded by one street due to the operation of the 30 second relay and not due to the operation of the 10 second relay, then the relay which 60 is energized by the ramps in the street which is just losing right of way, that is, relay 26 for A street or relay 21 for B street is not de-energized as it is when the right of way is yielded by the operation of the 10 second relay, but remains energized thus providing that the right of way return to this street immediately after a yellow period following the yielding by the other street.

This arrangement is made because when the right of way is yielded by the operation of the 30 second relay, a vehicle which has operated a ramp on the street which is losing right of way has not had a full 10 second period in which to cover the distance between the ramp and the intersection and to traverse the intersection. Thus it may 75 be stopped between the ramp and the intersection

by the red light. This circuit provides that the right of way return at the earliest permissible moment to this car without the necessity of further operation of a ramp in its street.

This effect is accomplished for A street as follows: The operation of 30 second relay 28 to release relay 32 does not de-energize relay 26 inasmuch as current is supplied through contacts 59 and 61. If, however, the right of way is yielded by 10 second relay 30, contact is broken between 59 and 61 thus de-energizing relay 26 when relay 34 is deenergized.

Where, in this description, a change of switch positions is indicated to produce a change in the effect on the signal means of actuation of an A street traffic actuated means, and another change of switch positions is further indicated to produce the same change in the effect on the signal means of actuation of a B street traffic actuated means, it is obvious that both changes in switch 20 positions could be made simultaneously, thus producing the aforesaid change in effect on the signal means by traffic actuated means in both or either streets.

The term "traffic actuated means" or the like is used in this specification and in the appended claims in the sense of traffic actuatable means or means adapted to be actuated by successive vehicles repeatedly.

Whereas, I have described a single street traffic control system embodying my invention, it is obvious that other arrangements embodying my invention may be constructed, and I do not wish to limit myself to the particular embodiment described herein. I aim in the appended claims to 35 cover all modifications which are within the scope of my invention.

What I claim as new and desire to secure by Letters Patent is:

1. In a highway traffic signal system for intersecting lanes, right of way signals for the respective lanes, traffic actuated means in each lane, a timing device for regulating the periods of operation of the signals, in accordance with traffic demand among the intersecting lanes as 45 revealed by the traffic actuated means, including means for maintaining periodic operation of the signals alternately in absence of actuation of the traffic actuated means.

2. In an automatic traffic signal system for 50 intersecting traffic lanes in combination, a plurality of signals at the intersection, electric control means for periodically operating the signals including a plurality of interlocking relays connected in circuit for selectively operating the signals at predetermined intervals in absence of traffic and traffic actuatable means for completing the circuits to certain of the relays whereby the period of operation of the signals may be 55 changed by the passage of traffic in either of the 60 lanes.

3. A signal system for intersecting traffic lanes comprising means for indicating right of way signals for the respective lanes, means actuated by traffic in the respective lanes to operate the signal indicating means, means connected with the signal indicating means and the traffic actuated means, including interconnecting means for controlling the period of time which may elapse between the actuation of the traffic actuated means on one lane and the operation of the signal by the traffic actuated means of another lane, means for controlling the period of time which may elapse between the actuation of the traffic actuated means by a vehicle or vehicles 75

- on said other lane and the operation of the signal so as to interrupt a continuous traffic stream on said one lane and means for operating the signal means in absence of actuation of the traffic actuated means in a periodic time sequence and traffic lane sequence.
4. A system of traffic control for use at the intersection of traffic lanes, comprising a traffic actuated means in each lane, signal means including a caution signal and "stop" and "go" right of way signals for the respective lanes, and a control mechanism interposed between said traffic actuated means and said signal means for causing a caution signal to show in all lanes when no traffic is immediately approaching the intersection, said control mechanism including means for causing a "go" signal to indicate right of way to that one of the intersecting lanes upon which traffic shall first approach said intersection and to cause said "go" signal to remain with this lane for a predetermined period after each vehicle thereon shall approach the intersection within a predetermined limiting period, means for causing the "go" signal to be withdrawn from said lane when no vehicle approaches during one of the first mentioned predetermined periods, means for maintaining the "go" signal when vehicles continue to approach at intervals of shorter time than said first mentioned predetermined period and withdraw right of way from said lane at the expiration of the second mentioned predetermined period, means for granting right of way immediately or after a caution period to that traffic lane upon which a vehicle approached said intersection subsequent to the approach of the vehicle which caused right of way to be granted to the lane from which it was last withdrawn.
5. In a traffic signal system, the combination with stop and go signals at a highway intersection, of means including an instantaneous relay for each highway and operated by a vehicle on its highway, an instantaneous signal relay for each highway, each connected to control a stop and go signal to accord right of way to its associated highway only, a delayed action relay for each highway connected with the instantaneous relays of that highway to time such accord of right of way, and means including an operating circuit for each signal relay interrupted by operation of the other signal relay and also interrupted by operation of its connected delayed action relay at the end of the time period of the latter to prevent the simultaneous operation of both instantaneous signal relays to operate stop and go signals.
6. In a traffic signal system, the combination with stop, go and caution signals at a highway intersection of means including an instantaneous relay for each highway connected to be energized by a vehicle on its highway, an instantaneous signal relay for each highway, each connected to control a stop and go signal to accord right of way to its associated highway only, a delayed action relay for each highway connected with the instantaneous relays of that highway to operate the signal relay responsive to operation of the traffic actuated relay to maintain right of way accorded only to that highway for a predetermined time period and to release said signal relay at the end of said time period, and means for actuating the caution signal when neither signal relay is so operated.
7. In a highway traffic signal system for intersecting streets comprising a plurality of signal lights for the respective streets, a timing mechanism having a predetermined period of operation for normally operating said signals in a predetermined sequence in absence of traffic, said timing mechanism including means for maintaining a desired signal on one street for a predetermined period, means actuated by traffic in an intersecting street for interrupting the predetermined period and for causing the desired signal to be given to said intersecting street and timing means for reestablishing the signal on the first street after a predetermined interval.
8. In a highway intersection traffic signal system comprising a plurality of right of way signal lights for the respective intersecting highways, a mechanism having a predetermined time rate of operation for normally operating the signal lights in sequence and controlling the duration of the periods of operation of the signal lights in the absence of traffic, said mechanism including means for changing the normal duration of the period of operation of the signal lights in response to traffic approaching the intersection.
9. In a highway signal system for intersecting streets having a signal means for each street for indicating right of way, means for receiving traffic presence indications from each street, including means for retaining the effect of such indications, and means for retaining the effect of the first such traffic indication until the signal means has indicated the right of way signal to that street for a continuous predetermined period after the last received traffic presence indication from that street, and a timing mechanism to time the continuous predetermined period through which the signal means indicates the right of way signal after the last received traffic presence impulse, said timing mechanism having an operating circuit and adapted to be energized to time its period by completion of said operating circuit and to reset to restart its timing responsive to interruption of said operating circuit, and a control switch in said operating circuit and opened by each operation of said traffic indicating means to interrupt said operating circuit responsive to each traffic presence indication.
10. In a highway signal system for intersecting streets having a signal means for each street for indicating right of way; means for receiving traffic presence indications from each street, including means for retaining the effect of such indications, and means for retaining the effect of the first such traffic indication until the signal means has indicated the right of way signal to that street for a continuous predetermined period after the last received traffic presence indication from that street, a timing mechanism to time the continuous predetermined period through which the signal means indicates the right of way signal after the last received traffic presence impulse, said timing mechanism having an operating circuit and adapted to be energized to time its period by completion of said operating circuit and to reset to restart its timing responsive to interruption of said operating circuit, and a control switch in said operating circuit and opened by each operation of said traffic indicating means to interrupt said operating circuit responsive to each traffic presence indication, and a second timing mechanism to control the maximum length of the time period which one street may be given the right of way indication by the signal means before the

right of way indication is given to the other street.

- 5 11. In an automatic traffic signal system for intersecting traffic lanes, in combination, a plurality of signals at the intersection, electric control means for periodically operating the signals including a plurality of interlocking relays connected in circuit for selectively operating the signals at predetermined intervals, and traffic actuated means for completing the circuits to certain of the relays whereby the period of operation of the signals in both streets may be changed by the passage of traffic in either of the lanes.
- 15 12. In an automatic traffic signal system for intersecting traffic lanes, in combination, a plurality of signals at the intersection, electric control means for periodically operating the signals including a plurality of interlocking relays connected in circuit for selectively operating the signals at predetermined intervals in absence of traffic, and traffic actuated means for completing the circuits to certain of the relays, whereby continuous traffic in one lane shall be interrupted to permit passage of a vehicle in an intersecting lane within a predetermined time after the arrival of such vehicle, but only for a predetermined period to permit passage of said vehicle.
- 25 13. In a vehicle actuated highway traffic signal system comprising a plurality of signal lights for intersecting highways, a mechanism having a predetermined period of operation for normally operating said signal lights in sequence and fixing the sequence and duration of the periods of operation of the signal lights in absence of traffic, said mechanism including means for changing the duration of the period and the sequence of operation of the signal lights in response to traffic approaching in at least one highway.
- 30 14. In a highway traffic signal system comprising a plurality of signal lights for intersecting highways, a mechanism having a predetermined period of operation for normally operating said signal lights and fixing the sequence and duration of the period of operation of the signal lights in absence of traffic, said mechanism including means for changing the duration of the period and the sequence of operation of the signal lights in response to traffic approaching in at least one highway, and means for preventing right of way signals being given to traffic simultaneously from two or more lanes.
- 35 15. A traffic signaling apparatus for two interfering traffic lanes and having, in combination, right of way indicating means for the respective lanes, traffic actuated controllers, one in each of said lanes, a timing mechanism for limiting right of way indication in either lane between an original, predetermined, minimum interval and a predetermined, maximum interval of time by actuation of the controller for such lane and at the end of such interval to terminate such right of way indication and assume a neutral signal condition with right of way indications in neither lane in absence of further actuation therein, and means to transfer right of way indication between said lanes, said transfer of right of way being dependent upon actuation of a controller in either lane before the end of any minimum interval indication or of any continuously prolonged minimum interval indication of right of way, less than the maximum, begun in the other lane by the other controller.

16. In a traffic signalling system for interfering traffic lanes, having means for displaying right of way signal indications, signal timer means for normally cyclically displaying said right of way indications successively to the several traffic lanes, a vehicle responsive device on one of said lanes, and super control means operable by response of said device to a vehicle on said one lane, to render said timer ineffective to normally display said indications, and to give the right of way indication to the said one lane. 10

17. In a traffic system for interfering lanes, a right of way indicating means displaying said indication to each of said lanes for predetermined times for the control of traffic, a vehicle actuated device in one of said lanes, and means operable upon actuation of said device when the said lane has the right of way for cooperating with the first named means to extend the time of display of said indication to the said one lane beyond the time predetermined by the first named means. 15

18. In a traffic system for intersecting streets, a right of way indication, means displaying said indication to each of said streets for predetermined times for the control of traffic, a vehicle actuated device in each street, and means operable upon an actuation of the device in the street having the right of way for cooperating with the first named means to extend the time of display of said indication beyond the time determined by the first named means. 20 25

19. In a traffic system for intersecting streets, a right of way indication, means displaying said indication to each of said streets for predetermined times for the control of traffic, a vehicle actuated device in each street and means operable upon an actuation of the device in the street having the right of way for cooperating with the first named means to extend the time of display of said indication beyond the time determined by the first named means, and means to further extend the time of display of said right of way indication upon subsequent actuations of the said device in the street having the right of way occurring within predetermined intervals of each other. 30 35 40

20. A device as in the preceding claim further provided with means for limiting such extended time of display of the right of way to the said street to a predetermined maximum time. 45 50

21. A right of way indicating device for intersecting main and cross thoroughfares, controller means for normally periodically shifting the right of way indication from one thoroughfare to the other, means to arrest the operation of the controller so as to maintain the right of way indication on the main thoroughfare, and means including a vehicle operated device on the main thoroughfare to operate the controller arresting means to maintain the right of way indication on the main thoroughfare, and means operable within a predetermined time after the said arresting means has functioned to re-establish the periodic control of the indication by the said controller. 55 60 65

22. In a traffic signal system arranged at the intersection of a main highway and a cross road for regulating traffic, said system comprising a plurality of signal circuits, one circuit including a signal to indicate "stop" and another to indicate "go," a time control selective switch means normally associated with said circuits for alternately opening and closing same cyclically, vehicular actuated means for rendering the said 70 75

- time control selective switch means temporarily inactive and to retain said "go" signal for the main highway, and a second time control switch means operable within a predetermined time after said selective switch has been rendered inactive to destroy the efficacy of the said vehicle actuated means to retain the "go" signal for one complete cycle.
23. In a traffic signaling system arranged at the intersection of a main highway and a cross-road for regulating traffic, the system comprising a plurality of signal circuits, said circuits including a "stop" signal for each of said highways and a "go" signal for each of said highways, a time control selective switch means normally connected to the said circuits for alternately opening and closing same cyclically, vehicular actuated means for rendering the said time controlled selective switch means temporarily inactive and to retain the said "go" signal for the main highway, and a second time control means, ineffective during the display of the "stop" signal to the main highway and operable to destroy the efficacy of the said vehicular actuated means to retain the "go" signal for one complete cycle within a predetermined time after the said main highway "go" signal is retained energized through the arresting of the said selective switch means after the extinction of the display of the said last "stop" signal.
24. In a signal system for intersecting traffic lanes the combination of right of way signals for the respective lanes, traffic actuatable means in each of the lanes, electro-magnetic means for operating the respective signals, electro-magnetic control means operated by actuation of the respective traffic actuatable means and an electric time controlled mechanism connected in circuit between the electro-magnetic signal operating means and the electro-magnetic control means of each lane to operate the right of way signals alternately in a predetermined time sequence in absence of actuation of said electro-magnetic control means and including means to interrupt the predetermined time sequence for a predetermined time interval in either lane responsive to actuation of the electro-magnetic control means for the latter lane.
25. In a traffic signal system for intersecting highways, "stop" and "go" signals for each of the respective highways, means including an instantaneous relay for each highway operated by passage of a vehicle on its highway, an instantaneous signal relay for each highway to operate a "stop" and "go" signal to accord right of way to its associated highway only, and a plurality of delayed action relays for each highway connecting the instantaneous relays of that highway to control the time of such operation of the "stop" and "go" signals by the signal relay responsive to actuation of the traffic operated relay and means controlled by said delayed action relays for interlocking the instantaneous signal relays so as to prevent the operation of more than one signal relay at the same time.
26. In a traffic signal system for intersecting lanes, a plurality of right of way signal means for the respective lanes, time controlled means for operating the signal means normally in sequence at periodic intervals, means responsive to a vehicle in one of the lanes for changing the period of operation of one of said signal means by said time controlled means, and means forming a part of said time controlled means for preventing operation of right of way signals simultaneously in more than one lane.
27. In a traffic signal system for intersecting lanes, a plurality of "go" signal means for the respective lanes, traffic actuated means for the respective lanes, timing mechanism connected with the traffic actuated means and the signal means to operate the signal means in one lane for a predetermined period, said timing mechanism including means for interrupting the first signal and operating the signal of an intersecting lane at the end of said period for another predetermined period in absence of traffic on said intersecting lane and means for restoring the "go" signal to the first lane at the end of said second period in the absence of traffic thereon, and means responsive to actuation of said traffic actuated means in said intersecting lane to prolong said second period.
28. In a vehicle actuated highway intersection traffic signal system comprising a plurality of right of way signal means and a caution signal, traffic actuatable means in the respective highways, timing mechanism having a predetermined time rate of operation for normally operating alternately in a time sequence the right of way signal for one highway and the caution signal in absence of traffic actuation, said mechanism including means for changing the normal sequence of operation of the signals to include operation of a right of way signal for the other highway for a time period responsive to actuation of said traffic actuatable means on said other highway and to restore the normal sequence at the end of said time period, and means for preventing operation of right of way signals on more than one highway simultaneously.
29. In a vehicle actuated highway traffic signal system comprising a plurality of right of way signal lights for intersecting highways, timing mechanism having a predetermined time rate of operation for normally operating said lights in sequence and controlling the duration of the periods of operation of the lights in absence of traffic, vehicle actuatable means in at least on highway, said mechanism including means for increasing the normal duration of the period of operation of the signal light on said one highway in response to vehicle actuation thereon.
30. In a traffic signaling apparatus for two interfering traffic lanes having right of way indicating means for the respective lanes, traffic actuatable controllers in the respective lanes, and time controlled mechanism for operating the indicating means in the respective lanes alternately for variable time periods in response to actuation of the respective controllers in accordance with traffic demand, said mechanism including timing devices individual to the respective lanes to limit operation of the right of way indication in each lane between an original predetermined minimum time interval and a greater predetermined maximum time interval by actuation of the controller for such lane.
31. In a traffic signaling apparatus for two interfering traffic lanes having right of way signals for the respective lanes, traffic actuatable controllers in the respective lanes, and time controlled mechanism for operating the signals in the respective lanes alternately for variable time periods in response to actuation of the respective controllers in accordance with traffic demand, said mechanism including switching mechanism having alternate switch positions for energizing

ing the respective right of way signals, two timing devices individual to each lane one having a relatively short predetermined minimum time period and the other having a considerably longer predetermined maximum time period, and connections between said switching mechanism and said timing devices to energize both said two devices of either one lane for timing in the switch position energizing the right of way signal for 5 said one lane, and means including connections actuated by said two timing devices to control said switch mechanism to hold the latter in the last mentioned position during the time periods of the respective two timing devices and at the 10 end of the period of either of the latter devices to release the switch mechanism from said last mentioned position for transfer to the other position, each said minimum timing device having a connection with the traffic actuated controller of its associated lane and being adapted to reset its 15 timing period responsive to actuation of such controller.

32. In a traffic signaling apparatus for two interfering lanes having a caution signal and right of way signals for the respective lanes, traffic actuated controllers for the respective lanes, and time controlled mechanism for operating the right of way signals in the respective lanes alternately for variable time periods in response 25 to actuation of the respective controllers in accordance with traffic demand, and operating the caution signal for a brief period intervening the alternate right of way signal periods, said mechanism including timing devices individual to the 30 respective lanes to control operation of the right of way signal in each lane individually so as to limit such operation between an original predetermined minimum time interval and a greater maximum time interval by actuation of the controller for such lane, and additional timing devices for the respective lanes connected to be 35 operated by the respective first named timing devices at the end of timing interval of the latter on one lane to operate said caution signal for a brief time interval and at the end of the 40 last named time interval to initiate such control of the right of way signal by the timing devices for the other lane.

33. In a traffic signaling apparatus for two interfering traffic lanes having right of way signals for the respective lanes, traffic actuated controllers in the respective lanes, and time controlled mechanism for operating the signals in the respective lanes alternately for variable time 45 periods in response to actuation of the respective controllers in accordance with traffic demand, said mechanism including switching mechanism having alternate switch positions for energizing the respective right of way signals, two timing devices individual to each lane one having a relatively short predetermined minimum time period 50 and the other having a considerably longer predetermined maximum time period, and connections between said switching mechanism and said minimum timing devices to energize said minimum device of either one lane for timing in the switch position energizing the right of way signal for said one lane, and connections between said switching mechanism and said maximum timing devices and including switch means operated by the respective controllers to energize the maximum timing device of either one lane responsive to traffic actuation on the other lane in the right of way switch position of said one lane, and means including connections actuated by said 55 two timing devices to control said switch mecha-

nism to hold the latter in the last mentioned position during the time periods of the respective two timing devices and at the end of the period of either of the latter devices to release the switch mechanism from said last mentioned position 5 for transfer to the other position in response to actuation of the controller for the other lane, each said minimum timing device having a connection with the traffic actuated controller of its associated lane and being adapted to reset its 10 timing period responsive to actuation of such controller.

34. In a traffic-signaling system, the combination of signals operable to indicate the right of way to several intersecting streets successively 15 and for simultaneously indicating stop to the others, signal switch mechanism operable to several positions to energize the necessary signal combinations in each of its several positions granting the right of way to said intersecting 20 streets respectively, said mechanism including switches operated for so energizing the several signals in the respective right of way positions and an interlocking connecting between said switches to prevent concurrent operation of the 25 switches for the respective right of way signals, vehicle-actuated devices in each of said streets, and timing switches for the respective streets and operable respectively responsive to actuations of said vehicle-actuated devices in the intersecting 30 streets to control the positioning of said signal switch mechanism and for maintaining said signal switch mechanism in a selected position granting right of way for a minimum time period responsive to a single actuation of a vehicle-actuated device. 35

35. In a traffic signalling system, the combination of signals operable to indicate the right of way to several intersecting streets successively 40 and for simultaneously indicating stop to the others of said streets, signal switch mechanism operable to several positions to energize the necessary signal combinations in each of its several positions granting the right of way to said intersecting streets respectively, said mechanism including switches operated for so energizing the several signals in the respective right of way positions and an interlocking connection between said switches to prevent concurrent operation of the switches for the respective right 45 of way signals, vehicle-actuated devices in each of said streets, and timing switches for the respective streets and operable respectively responsive to actuations of said vehicle-actuated devices to operate said signal switch mechanism to assume a predetermined position granting right 50 of way responsive to an actuation of a vehicle-actuated device in one of the intersecting streets, to hold said signal switch mechanism in said position for a predetermined minimum time period and to hold said signal switch mechanism in said position for a predetermined maximum time period responsive to successive actuations 55 of said vehicle-actuated device, said actuations being spaced from each other a time period less than said minimum period. 60

36. In a traffic-signaling system the combination of signals positioned at the intersection of two thoroughfares and operable to alternately indicate the right of way to each of said thoroughfares respectively while indicating stop to the other, vehicle-actuated devices in each of said thoroughfares, relays responsive to actuations of said vehicle devices in the thoroughfares respectively and operable to record the pres- 75

ence of vehicles at the intersection on the thoroughfares not having the right of way, a timing switch for each of said thoroughfares operable responsive to the setting of the relay corresponding to the vehicle-actuated device in one thoroughfare, and signal switch mechanism operated responsive to the joint action of said timing switches to energize said signals to maintain the right of way on one thoroughfare for a pre-determined minimum time period by one timing switch responsive to a single actuation of a said vehicle-actuated device in that thoroughfare and to transfer the control of said signals to the second of said timing switches at the end of this period, said signal switch mechanism including switches for so energizing the signals to grant right of way to the respective thoroughfares and an interlocking connection between said switches to prevent concurrent operation of the switches for the respective right of way signals.

37. In a traffic signalling system for two intersecting streets, a right of way signal for one of the streets, a switch operable for energizing said signal, a traffic actuated device for said one street, and a timing switch for said one street, a second right of way signal for the second street, a second switch operable for energizing said second signal, a traffic actuated device for said second street, and a timing switch for said second street, and operating mechanism for the signal switches and having two alternate interlocked positions, one for operating only the first mentioned switch to accord right of way to the first street and the second position for operating only the second switch to accord right of way to the second street, and connections between said mechanism and the two sets of timing switches and traffic actuated devices for the two streets to control shift of said mechanism from either one position to the other to accord right of way responsive to actuation of the respective devices in the street not having right of way, and to maintain said mechanism for a minimum time period by one timing switch in either one position to which said mechanism is so shifted in response to a single actuation of one traffic actuated device and to release control of said mechanism to the other traffic actuated device at completion of the time period of the last mentioned one timing switch for shift from the last mentioned one position of said mechanism to the other position responsive to actuation of said other traffic actuated device.

38. In a traffic signalling system for two intersecting streets, a right of way signal for one of the streets, a switch operable for energizing said signal, a traffic actuated device for said one street, and a minimum period timing switch and a maximum period timing switch for said one street, a second right of way signal for the second street, a second switch operable for energizing said second signal, a traffic actuated device for said second street, and a minimum period timing switch and a maximum period timing switch for said second street, and operating mechanism for the signal switches and having two alternate interlocked operating positions, one for operating only the first mentioned switch to accord right of way to the first street and the second position for operating only the second switch to accord right of way to the second street, and connections between said mechanism and

the two sets of timing switches and traffic actuated devices for the two streets to control shift of said mechanism from either one position to the other to accord right of way responsive to actuation of the respective devices in the street not having right of way, said connections including operating connections for the timing switches from said mechanism to operate the respective minimum and maximum timing switches for timing in the respective right of way signalling positions and also including operating connections for said mechanism from the respective minimum and maximum timing switches for one street and from the traffic actuated device for the second street to shift said mechanism from said one position to said second position responsive to traffic actuation of the second traffic actuated device and to completion of timing by either one of said one minimum and said one maximum timing switches, an operating connection for said mechanism from the minimum and maximum timing switches for the second street and from the traffic actuated for said one street to shift said mechanism from said second position to said one position responsive to traffic actuation of said one device and to completion of its timing by either one of said second minimum and said maximum timing switches, and a controlling connection between the traffic actuated device on each street and the minimum timing switch for that street to interrupt completion of the timing of the minimum timing switch to maintain right of way beyond the minimum period and up to the maximum period by repeated traffic actuations.

39. A traffic control system for use at the intersection of a plurality of traffic lanes, comprising a vehicle-actuated means in each lane placed for actuation by vehicles approaching the intersection, a caution signal and right of way signal means for each lane, a controlling means interposed between said vehicle-actuated means and said signal means, said controlling means including means to operate a right of way signal to that lane from which vehicles shall first approach said intersection, means for maintaining said right of way until a vehicle approaches said intersection from another of said intersecting lanes and holding said right of way thereafter for a predetermined period after the approach of each vehicle on the first lane within another predetermined limiting period, means to withdraw said right of way upon the expiration of one of the first mentioned predetermined periods after such approach of a vehicle in said other lane when vehicles cease approaching on said first lane for an interval greater than said first mentioned predetermined period, and means for withdrawing the right of way at the expiration of the second mentioned predetermined limiting period after such approach of a vehicle on said other lane when vehicles constantly approach said intersection at intervals less than the first mentioned predetermined period, and means operating upon such withdrawal of right of way by either of the right of way withdrawal means to grant right of way to said other of said intersecting lanes upon which a vehicle so approached said intersection after right of way was granted to the first lane and to provide a period of caution signal operation between such withdrawal and such grant of right of way.

HENRY A. HAUGH, JR.
